8 Claims. (Cl. 250—11)

This invention relates to a method of and arrangement for ascertaining direction in taking bearings of electro-magnetic waves.

In order to ascertain furthermore the sense of direction of electro-magnetic rays for which bearing has already been established by means of a frame antenna, it is a customary method to use a linear auxiliary antenna whose voltage is combined in such manner with that supplied by the directive antenna, that the directional receiving characteristic assumes the shape of a cardioid. In order to determine the sense of direction, the directive antenna is placed into the position in which the reception is a maximum 10. 15. 20. 25. 30. 35. 40. 45. 50. 55. 60. 65. 70. 75. 80. 85. 90. forms with the direction determined by the fixed zero line of the scale an angle of α ° or an angle ($\alpha + 180$ °). In order to determine the sense of direction the direction indicating wheel is moved 5 in either direction approximately 90°, so that either the blue auxiliary pointer B or the red auxiliary pointer R is above the indicating line for the angle α of the scale. The blue auxiliary pointer may be assumed to be at this position. 10 Now, the switch s (see Figure 1) will be moved alternately several times to the left and the right resistances h_1 and h_2 and will be left to remain upon the field for which the signal strength is the greatest. If this is the field marked in blue 15 then the sense of direction corresponds with the position of the blue auxiliary pointer B i. e. with the angle α °. In the other case i. e. if the greater signal strength occurs at the position of the pointer above the red field, the sense of direction 20 of the directive rays corresponds with the position of the red auxiliary pointer E, i. e. with the angle ($\alpha + 180$ °).

In this manner the switch s can at the same time be used as an indicator for the recognition 25 of the sense of direction.

It is obvious that it is within the same spirit of the invention if as directive antenna instead of a closed frame an antenna formed in any other way, is used, such as an Adcock-antenna. 30 An embodiment of this type is shown in Figure 3 by way of example. The directive antenna is formed of two open vertical conductors aa, which are preferably arranged movable about a symmetrical axis between these conductors. 35 The two conductors aa of the directive antenna are connected to the intermediate circuit by means of coupling transformers kk and which circuit supplies the input circuit of the high frequency amplifier e which forms the first stage 40 of the receiver. The auxiliary antenna b is arranged at the center between the conductors aa. Otherwise the circuit for the auxiliary antenna corresponds with that of Figure 1.

It is advisable in particular when operating 45 with very short waves to provide the amplifiers didz with screen grids as shown in order to prevent an eventual undesirable coupling of the auxiliary antenna with the direction finding receiver across the grid to anode capacity.

Having thus described my invention, what I 50 claim is:

1. A direction determining receiver including a non-symmetrical signal absorption member, a thermionic tube connected therewith by way of 55 tuning means, and means for determining the sense of direction of received signals comprising a pair of thermionic tubes having their anodes connected to different sides of said absorption member, their control grids connected to a non-direction aerial, and means for alternately rendering said last named tubes operative and inoperative.

2. Direction and sense of direction determining absorption system comprising, a directive aerial 65 system, a non-directive aerial, a pair of thermionic tubes having their input electrodes connected to said non-directional aerial, and a connection between each terminal of said directive aerial and the output electrode in one of said tubes.

3. A direction finding system comprising in combination a loop aerial connected to a thermionic tube having input and output circuits, a non-directional aerial continuously coupled with

the input circuit of two thermionic tubes having the output of each one of said tubes continuously connected to opposite sides of said loop aerial, means to determine the sense of direction, said means controlling the activation of either one of said thermionic tubes which are coupled with said non-directional aerial.

4. A direction finding system comprising in combination a loop aerial connected to a thermionic tube having input and output circuits, a non-directional aerial continuously coupled with the input circuit of two thermionic tubes having the output of each one of said tubes continuously connected to opposite sides of said loop aerial, means to determine the sense of direction, switching means comprising a common switch arm and separate variable resistance elements to vary the heater voltage of either one of said thermionic tubes which are coupled with said non-directional aerial.

5. A direction finding system comprising in combination a loop aerial connected to a thermionic tube having input and output circuits, a non-directional aerial continuously coupled with the input circuit of two screen grid tubes having the output of each one of said tubes continuously connected to opposite sides of said loop aerial, means to determine the sense of direction, said means controlling the activation of either one of said screen grid tubes which are coupled with the non-directional aerial.

6. A directive antenna system comprising two open vertical conductors, said conductors arranged to be movable about a symmetrical axis between said conductors, transformer coupling means for coupling said conductors to the input circuit of a high frequency receiver amplifier, an auxiliary antenna continuously connected with the input circuit of two screen grid tubes having the output of each one of said tubes continuously connected to opposite sides of said vertical conductor couplings, means to determine the sense of direction, said means controlling the activation of either one of said screen grid tubes.

7. A directive antenna system comprising two open vertical conductors, said conductors arranged to be movable about a symmetrical axis between said conductors, transformer coupling means for coupling said conductors to the input circuit of a high frequency receiver amplifier, an auxiliary antenna continuously connected with the input circuit of two screen grid tubes having the output of each one of said tubes continuously connected to opposite sides of said vertical conductor couplings, means to determine the sense of direction, switching means comprising a common switch arm and separate variable resistance elements to vary the heater voltage of either one of said screen grid tubes which are coupled with the vertical conductors.

8. A direction finding system comprising in combination a loop aerial connected to a thermionic tube having input and output circuits, a non-directional aerial continuously coupled with the input circuit of two thermionic tubes having the output of each one of said tubes continuously connected across condensers to opposite sides of said loop aerial, means to determine the sense of direction, said means controlling the activation 70 of either one of said thermionic tubes which are coupled with said non-directional aerial.

WALTER KÜHLEWIND.
